UNITED STATES PATENT OFFICE.

BENEDICT MAYER, OF NEW ORLEANS, LOUISIANA.

WINDOW.

Application filed April 12, 1926. Serial No. 101,494.

My invention relates to steel windows and especially to a steel sash section having pivotal means to be disposed at an angle to the plane of the window. In sashes of the type to which the invention relates, the roller pivot has a permanent form and does not permit of adjustment so that the pivot means cannot be varied to suit windows slightly varying in width and the pivot when the sash is in plumb, or when it is dented or winding, causes the window to bind.

The general object of my invention is to provide pivot means for a sash section so constructed and arranged as to permit of adjustment of the pivot to vary the total transverse dimensions of the window at the pivot line and to permit of the swinging of the sash section even though the latter be bent or otherwise deformed.

The nature of my invention and its distinguishing features and advantages will more clearly appear as the description proceeds.

Reference is to be had to the accompanying drawings forming a part of this specification, it being understood that the drawings are merely illustrative of one example of the invention.

Figure 1 is a front elevation showing a swingable sash section equipped with my invention and portions of permanently mounted sash sections above and below the swingable sash section.

Figure 2 is a side view of the sash of the window, the near vertical channel bar of the window frame being omitted so that the sash section and its novel appurtenances appear in edge view with the far vertical frame bar in elevation.

Figure 3 is a detail in vertical section at one of the pivots;

Figure 4 is an end view at one end of a pivoting unit.

Figure 5 is a view at the opposite end of the pivot unit.

In the illustrated example of my invention, the numeral 10 indicates a movable sash section; 11 and 12, upper and lower fixed sash sections; and 13 indicates the vertical channel bars or jambs of the window frame.

The sash section 10 is provided with a unit for pivotally mounting the same at each side.

55 The unit comprises a transverse pivot pin 14 supported in spaced upright members 15,

16 rising from a base plate 17 which is riveted to the meeting rail 18 of said sash section. The pivot pin 14 has a head 19 at the outer end thereof disposed in a roller 20 socket 20 which is adapted to be disposed in the frame bar 13 which is of channel form. A spring 21 is coiled about pivot pin 14 between the roller 20 and the adjacent upright members 16 which constitutes a fixed 65 abutment for the spring. The spring 21 permits of the roller 20 being brought toward or from the abutment 16 for adjusting the pivot and for emplacing the roller 20 in the channel frame bar 13. The inner 70 end of the pivot pin 14 which passes through the upright member 15 is adapted to be fastened for holding the pin 14 in adjusted position, a set screw 22 in member 15 being provided for the purpose. 75

By loosening the set screw 22 and releasing the pin 14, said pin may be moved outward or inward to accommodate itself to the window frame conditions and then with the two opposite rollers 20 at the respective 80 sides of the sash section 10 in contact with the vertical frame bars 13, the set screw is fastened to hold the pin 14 in given adjustment.

Braces 23 are provided for the sash section 85 10 at opposite sides, said braces being pivotally secured at their upper ends as at 24 to said sash section and pivoted at the lower ends as at 25 to the channel bars 13. A side or flange of each of said channel bars 90 13 is cut away to afford clearance for the swinging of the braces to and from a position alongside the web of the channel bars 13.

With the sash section 10 equipped with the pivot units and braces as described, the sash 95 may be moved outward at an angle to the plane of the window frame shown in Figure 2, the rollers 20 being free to travel in the bars 13. When the window is swung inward into the plane of the upper and lower 100 permanent sections 11 and 12, the brace 23 folds along the sides of the sash section 10.

I would state furthermore that while the illustrated example constitutes a practical embodiment of my invention, I do not limit 105 myself strictly to the exact details herein illustrated, since, manifestly, the same can be considerably varied without departure from the spirit of the invention.

Having thus described my invention, I 110 claim:

1. In a window, a frame having vertical

channel bars at the sides, a sash section disposed between said vertical channel bars, transversely disposed pivot pins, means on the top bar of said section in which said pins are supported for inward and outward adjustment, means to secure the pivot pins in variously adjusted positions, rollers on said pivot pins at the outer ends and adapted to travel in the vertical channel bars, springs coiled about said pins and normally tending to press said rollers outwardly, and braces pivoted at their upper ends to said sash section at the sides and having members at their lower ends extending into said channel bars.

15. 2. A window sash section adapted to be disposed in a window frame, pivot pins at each side of said sash at the top, means mounting said pins and permitting a longitudinal adjustment thereof, and means for locking the pins in adjusted positions.

20. 3. A window sash section adapted to be disposed in a window frame, pivot pins at each side of said sash at the top, means

mounting said pins and permitting a longitudinal adjustment thereof and means for locking the pins in adjusted positions; together with rollers on said pins adapted to have guided movement in the sides of the window frame.

4. A pivot unit adapted to be secured to a window sash and including a base, vertical members on said base, a pivot pin adjustable longitudinally in said members, and means to secure said pin in adjusted position.

5. A pivot pin for a sash, comprising a base plate having spaced vertical apertured members; a pin mounted to slide in the apertures of said members, a roller mounted to slide and turn on the outer end of the pin, a spring on the pin and having one end engaging the outer member of the base plate and the other end engaging the roller, and a screw mounted in the inner member of the base plate and engaging said pin.

BENEDICT MAYER.
